HYDROFOIL

Renato Castellani, Via Baiettini 86,
Verbania Intra, Novara, Italy

Continuation-in-part of design application Ser. No.
3,602, Aug. 26, 1966. This application Feb. 5, 1968,
Ser. No. 10,452

Term of patent 14 years

(Cl. D71—1)

FIG. 1 is a side view of a hydrofoil shown with its front end at the left and its rear end at the right, showing my new design;

FIG. 2 is an end elevation of the hydrofoil as seen from the left of FIG. 1, thus showing the hydrofoil when looking toward the front end thereof, FIG. 2 being on a scale larger than FIG. 1;

FIG. 3 is a side view of the hydrofoil as seen from the side thereof which is not visible in FIG. 1, FIG. 3 thus showing the front end of the hydrofoil at the right of FIG. 3 and the rear end of the hydrofoil at the left of FIG. 3; and

FIG. 4 is a top plan view of the hydrofoil shown in FIG. 3.

This is continuation-in-part of design application Serial Number 3,602, filed August 26, 1966, now abandoned.

I claim:

The ornamental design for a hydrofoil, as shown.
